DESIGN FOR A TOY MANGLE

Walter Kasten, Franklin, and Adam Edward
Mason, Belleville, Mich.

Application February 9, 1946, Serial No. 126,413

Term of patent 7 years

(Cl. D34—15)

To all whom it may concern:

Be it known that we, Walter Kasten and Adam Edward Mason, citizens of the United States of America, residing respectively at Franklin, in the county of Oakland and the State of Michigan, and Belleville, in the county of Wayne and the State of Michigan, have invented a new, original, and ornamental Design for Toy Mangle, of which the following is a specification, reference being had to the accompanying drawing, forming part thereof.

We claim:

The ornamental design for a toy mangle substantially as shown.

WALTER KASTEN.
ADAM EDWARD MASON.
